DESIGN FOR AN AIRPLANE

Harland M. Poyer, Lewiston, N. Y., assignor to
Bell Aircraft Corporation, Buffalo, N. Y.

Application October 16, 1943, Serial No. 111,395

Term of patent 14 years

(Cl. D71—1)

To all whom it may concern:

Be it known that I, Harland M. Poyer, a citizen of the United States, residing at Ridge Road, Lewiston, county of Niagara, State of New York, have invented a new, original, and ornamental Design for an Airplane, of which the following is a specification, reference being had to the accompanying drawings, forming a part thereof.

Figure 1 is a top plan view of an airplane showing my new design;

Figure 2 is a side elevational view;
Figure 3 is a front elevational view;
Figure 4 is a rear elevational view thereof; and
Figure 5 is a fragmentary front perspective view.

I claim:
The ornamental design for an airplane, as shown.

HARLAND M. POYER.
